Primary Examiner — Jennifer L Rempfer*Assistant Examiner* — Adrienne Corra(74) Attorney, Agent, or Firm — Banner & Witcoff, Ltd.(57) CLAIM

The ornamental design for a shoe as shown and described.

DESCRIPTION

FIG. 1 is a bottom view of a shoe showing my new design; FIG. 2 is a bottom rear perspective view thereof; FIG. 3 is an opposite side bottom rear perspective view thereof; and, FIG. 4 is a rear view thereof.
The broken lines depicting the remainder of the shoe form no part of the claimed design.

1 Claim, 4 Drawing Sheets(56)
